DESIGN FOR A PIN

Willard Markle, New York, N. Y.

Application January 28, 1941, Serial No. 98,468

Term of patent 3½ years

To all whom it may concern:

Be it known that I, Willard Markle, a citizen of the United States, residing in New York city, in the county of New York and State of New York, have invented a new, original, and ornamental Design for Pins, of which the following is a specification, reference being had to the accompanying drawing, forming part thereof, in which—

I claim:

The ornamental design for a pin, as shown.

WILLARD MARKLE.
